UNITED STATES PATENT OFFICE.

FRANK ZAGMESTER, OF LA SALLE, NEW YORK.

DESIGN FOR A CONDIMENT-HOLDER.

52,864.

Specification for Design.

Patented Jan. 7, 1919.

Application filed October 10, 1918. Serial No. 257,666. Term of patent 7 years.

To all whom it may concern:

Be it known that I, FRANK ZAGMESTER, a Jugo-Slav, claimed as a subject of the King of Hungary, residing at La Salle, in the county of Niagara and State of New York, have invented a new, original, and ornamental Design for Condiment-Holders, of which the following is a specification, reference being had to the accompanying drawing, forming part thereof.

The figure is a view in perspective of condiment holder, showing my new design.

I claim:

The ornamental design for a condiment holder, as shown.

FRANK ZAGMESTER.
